UNITED STATES PATENT OFFICE.

JOHN WATTERS, OF NEW YORK, N. Y.

TOP-PROP BLOCK FOR CARRIAGES.

SPECIFICATION forming part of Letters Patent No. 238,541, dated March 8, 1881.

Application filed January 29, 1881. (Model.)

To all whom it may concern:

Be it known that I, JOHN WATTERS, of the city of New York, county of New York, and State of New York, have invented an Improved 5 Top-Prop Block, of which the following is a specification.

Figure 1 is a perspective view, and Figs. 2 and 3 are vertical cross-sections, of my improved top-prop block.

This invention relates to an improvement in top-prop blocks for carriages, which blocks have heretofore been made of india-rubber or other similar material, and which, although made of elastic material, being fastened upon 10 iron bars, are seldom sufficiently elastic to support the back-bow in its backward fall without unnecessary shocks. Now, if the top-prop block is not made quite elastic, it is liable to become cut by the back-bow, and also 15 to mar the latter, and a construction which will make the top-prop block perfectly elastic is very desirable.

To this end my invention consists in providing the cushion part of the top-prop block 20 with one or more air-channels that traverse it, thereby producing an air-cushion, which, be-

ing the most elastic of all substances available for this purpose, will overcome the difficulties pointed out.

In the accompanying drawings, the letter 30 A represents a top-prop block of the ordinary form, made of india-rubber or other analogous material.

My invention consists in forming the air-channel a through the cushion part b of this 35 block A. This air-channel a is a perforation extending preferably from end to end of the block, and is, by preference, formed longitudinally through the same, as indicated; but it may, if desired, be formed diagonally or in a 40 curved line through the block; or more than one such perforation may be supplied, if desired.

I claim—

A top-prop block made of elastic material 45 and provided with one or more holes, a, through its supporting part b, for the purpose of forming an air-cushion, substantially as described.

JOHN WATTERS.
